The ornamental design for vehicle wheel front face, as shown and described.

DESCRIPTION

FIG. 1 is a perspective view of a vehicle wheel front face according to our new design;

FIG. 2 is a front elevational view thereof;

FIG. 3 is a side elevational view thereof;

FIG. 4 is a perspective view of a second embodiment of a vehicle wheel front face according to our new design; FIG. 5 is a front elevational view of the second embodiment; and,

FIG. 6 is a side elevational view of the second embodiment. The broken lines represent portions of the vehicle wheel front face that form no part of the claimed design.
